CABLE EQUALIZER

Harry H. Vanderzee, Chicago, Ill., assignor to
Westinghouse Electric Elevator Company, Chi-
cago, Ill., a corporation of Illinois

Application August 8, 1934, Serial No. 738,982

6 Claims. (Cl. 187—1)

My invention relates to cable equalizers and more particularly to such equalizers as may be employed for equalizing the tension of the hoisting cables on elevator cars.

5 One object of my invention is to provide an equalizer to compensate for the ever changing lengths in cables and to distribute the load with equal tension on each cable supporting the car and counterweight, where a multiple cable system is used.

10 Another object is to provide an equalizer in which the attachment points of the cables to the equalizer are concentrated within close limits so as to keep the spread of the cables to a minimum.

15 A further object is to provide an equalizer of compact design which will occupy a relatively small space and which can be easily and quickly installed on any existing traction installation using a standard cross head construction.

20 It is also an object of my invention to provide a cable equalizer which will enable more mileage to be obtained from each cable, which will prevent excessive cable and irregular wear in the elevator sheave grooves and which will provide for maximum cable traction and efficient 25 operation.

For a better understanding of my invention, reference may be had to the accompanying drawing, in which

30 Figure 1 is a view in perspective of my improved cable equalizer for attaching the hoisting cables of an elevator car to the car structure or to its counterweight.

35 Fig. 2 is a view taken along the line II—II of Fig. 1, and

Fig. 3 is a view taken on the line III—III of Fig. 1.

40 The equalizer is illustrated in the drawing as provided with a frame 10 comprising a pair of heavy metal side plates 11 and 12 mounted on a pair of bars or pipes 13 and 14. For ease and simplicity in construction, the bars and plates are connected by passing the bars through a plurality of transverse holes 15 in the lower portions of the plates. A spacing plate 16 is attached to the bar 13 by a bolt 17 in position between the plates 11 and 12 and a similar plate 18 is mounted upon the bar 14 by means of a bolt 19, to maintain the side plates at a correct distance 45 from each other.

50 The bars 13 and 14 are provided near their outer ends with a plurality of metal clips 21 in order that the equalizer frame may be secured to an elevator car by passing the bars 13 and 14 underneath the flanged beams (not shown) which

usually constitutes the upper part of the car frame or sling and by then fastening the clips 21 against such flanged portions by means of a plurality of U-bolts 22.

5 A first equalizing lever 25 and a second equalizing lever 26 are mounted in the frame 10. The first lever comprises two spaced-apart parallel bars 27 and 28 disposed between the frame plates 11 and 12. A fulcrum pin 29 passes through the left hand ends of the bars 27 and 28 and thence 10 through suitable apertures in the side plates 11 and 12, thereby pivotally mounting the lever between the plates with its free end extending a short distance beyond the right-hand ends of the plates. A pair of cotter pins 30 are disposed in 15 the ends of the pin to hold it in position.

The second lever 26 is of less length than the lever 25 and comprises a pair of spaced-apart parallel plates 31 and 32 which are also disposed between the side plates 11 and 12 but above 20 the first lever 25. A fulcrum pin 33 passes through the second lever at a point a little to the left of its central portion and then through the side plates 11 and 12 near their upper right hand ends. The pin 33 is held in position by suitable cotter pins 34. In this position, the second lever is located a short distance above the first lever, approximately parallel therewith and in a vertical plane therewith.

25 The right-hand ends of the first and second 30 levers also end in approximately the same vertical plane and are pivotally connected by a link 35. The upper end of the link is disposed between the plates 31 and 32 of the lever 26 and is held in position by a pivot pin 36. The lower end 35 of the link is disposed between the plates 27 and 28 of the first lever and is held in position by a pivot pin 37. Suitable cotter pins 38 are provided for preventing the pins 36 and 37 from slipping out of their position. As a result of the connection made by the link 35, any force affecting either 40 lever will also affect the other lever.

A third equalizing lever 40 of less length than the second lever is mounted upon the first equalizing lever 25 at a point a short distance to the 45 left of the central portion of that lever. The lever 40 comprises a pair of spaced-apart parallel plates 41 and 42 disposed between the plates 11 and 12 of the first lever and held in position by means of a pivot pin 43. The pivot pin passes 50 through the central portion of the lever 40 to give the ends of that lever equal power. Suitable cotter pins 44 are provided to prevent the pin 43 from slipping out of position.

55 A draw-bar 46 is mounted on the left hand end

of the lever 40 by means of a suitable pivot pin 49. A similar draw-bar 47 is mounted upon the right hand end of the lever 40 by means of a suitable pivot pin 50. A draw-bar 48 is mounted 5 in the left hand end of the second lever 26 by means of a suitable pivot pin 52 which passes through the plates 31 and 32 and is held in position by suitable cotter pins 53. As indicated by the drawing, the lengths of the first, second and 10 third equalizing levers and the position of their fulcrum pins are such that the draw-bars 46, 47, and 48 are disposed an equal distance apart and are connected to the levers at points in the central portion of the equalizer.

15 The upper end of the draw-bar 46 is pivotally connected to a rocker bar 54 by a suitable pin 59. The upper end of the draw-bar 48 is pivotally connected to a rocker bar 55. The upper end of the draw-bar 47 is pivotally connected to a rocker bar 56. Each of the outer ends of the rocker bars is pivotally connected to a rope or cable socket 57 to which a hoisting cable or other draft member 58 is attached.

In operation, if the tension on one of the cables 20 25 58 attached to the rocker bar 54 increases over that on the other cable attached to that bar, the bar, by reason of its central pivotal mounting will immediately rotate to a position where the tension on each cable attached to it will be equal. 30 The tension on the cables attached to the rocker bars 55 and 56 will be equalized in the same manner. If the tension on the cables attached to the bars 54 and 56 increases over that applied to the bar 55, the upward pull on the draw-bars 46 and 47 will exert an upward pull on the first lever 25, which, by the link 35, will exert an upward push on the right-hand end of the lever 26 and thereby exert a downward pull on the draw-bar 48 and consequently the rocker bar 55 until the 35 tension forces are equal.

40 It will be noted also that if the tension on the rocker bar 54 increases over that on the rocker bar 55, the upward pull on the third lever 40 by the draw-bar 46 will exert such a downward pull on the draw-bar 47 as will equalize the tension between the rocker bars 54 and 56.

The maximum difference in permanent cable elongation which an equalizer will compensate for is determined by the length of the rocker bars 54, 55, and 56, which divide the cables into pairs and to which they are attached. Since it is desirable to keep the cables as close together as possible at the point of attachment to the car to minimize and lead upon the driving sheave, the length of 50 these pairs should be as short as the requirements of the equalizer will permit. A length of approximately seven inches is sufficient if the equalizer is correctly designed. This length will permit a difference in cable elongation of approximately five inches between cables attached to the same rocker bar. This figure is somewhat greater for two cables not attached to the same upper rocker bar because of the travel available to equalize the bars by the first, second, and third 55 levers.

60 It will also be seen that, by reason of the central position of the draw-bars and the rocker bars, the hoisting cables are centralized in such manner that they will track accurately in corresponding grooves in the hoisting drum (not shown) over which they operate.

65 Excessive equalizer travel is not desirable because it is one of the factors which determines the distance the car would fall in the event of a 70 cable break, and it is important that this be kept

75 to a minimum. Therefore, the equalizer should not be regarded solely as a device for eliminating the necessity for cable adjustment. Its purpose should be to not only equalize the tension on the cables but also to make visible to the inspectors 5 the fact when adjustment is necessary and to maintain an equal load distribution until the adjustment can be made.

Although I have illustrated and described only one specific embodiment of my invention, I realize 10 that it is susceptible of wide application, and I do not desire to be limited to the precise construction illustrated and described.

I claim as my invention:

1. In an equalizer for connecting a body to a 15 plurality of draft members, a pair of side plates, a first lever, a fulcrum pin for pivotally connecting one end of the first lever to one portion of the side plates, a second lever of less length than the first lever and disposed above the first lever, 20 a fulcrum pin for pivotally connecting the middle portion of the second lever to another portion of the side plates, a third lever of less length than the second lever, means for pivotally connecting the central portion of the third lever to 25 the portion of the first lever lying between the fulcrum pins of the first lever and the fulcrum pin of the second lever, a plurality of draw-bars, one connected to each of the ends of the third lever and to the inner end of the second lever, 30 and a link pivotally connecting the outer end of the second lever and the free end of the first lever to equally distribute the load of the body on the draw-bars.

2. In an equalizer for connecting a body to a 35 plurality of hoisting cables, a first horizontal lever, means for pivotally connecting one end of said lever to said body, a second horizontal lever, means for pivotally connecting the middle portion of the second lever to said body, a 40 third horizontal lever, means for pivotally connecting the middle portion of the third lever to a near middle portion of the first lever, a first draw-bar connected to one end of the third lever, a second draw-bar connected to the other end 45 of the third lever, a third draw-bar connected to the inner end of the second lever, and means for pivotally connecting the outer end of the second lever to the free end of the first lever whereby the load of the body is equally distributed on 50 the draw-bars.

3. In an equalizer for connecting an elevator body to a plurality of hoisting cables, a first lever having one end pivotally connected to the body, 55 a second lever of less length than the first lever and disposed above the first lever and having its outer end disposed in approximately vertical alignment with the free end of the first lever, means for pivotally connecting a near middle portion of the second lever to the body, means 60 for pivotally connecting the outer end of the second lever and the free end of the first lever, a third lever of less length than the second lever, means for pivotally connecting the central portion of the third lever to a near middle portion 65 of the first lever, a first rocker-bar, a second rocker-bar, a third rocker-bar, means for connecting a cable to each end of each rocker bar, a first draw-bar pivotally connecting the middle portion of the first rocker-bar to one end of 70 the third lever, a second draw-bar pivotally connecting the second rocker-bar to the other end of the third lever, and a third draw-bar pivotally connecting the third rocker-bar to the inner end of the second lever equally distributing the 75

- load of the body on the cables and maintaining them near the center of the equalizer.
4. In an equalizer for connecting a plurality of hoisting cables to an elevator body, a first lever having one end pivotally connected to the body, a second lever of less length than the first lever and disposed above the free portion of that lever and having its outer end aligned with the free end thereof, means for pivotally connecting the outer end of the second lever to the free end of the first lever, means for pivotally connecting the middle portion of the second lever to the body, a third lever of less length than the second lever, and being disposed below the second lever, means for pivotally connecting the middle portion of the third lever to that portion of the first lever lying beneath the inner end of the second lever, a plurality of draw-bars connected respectively to the inner end of the second lever and the outer ends of the third lever, a rocker-bar for each draw-bar, means pivotally connecting the middle portion of each rocker-bar to its draw-bar, and means for pivotally connecting a cable to each end of each rocker-bar for equally distributing the load of the body on the cables and maintaining them in a centralized group.
5. In an equalizer for connecting an elevator body to a plurality of hoisting cables, a first lever pivotally connected at one end to the load, a sec-

ond lever of less length than the first lever and disposed above the first lever in a vertical plane therewith, means for pivotally connecting the outer end of the second lever to the free end of the first lever, means for pivotally connecting the middle portion of the second lever to the body, a third lever disposed below the second lever, means for pivotally connecting the central portion of the third lever to the portion of the first lever lying below the inner end of the second lever, a draw-bar connected to the inner end of the second lever, a draw-bar connected to one end of the third lever and a draw-bar connected to the other end of the third lever, whereby the load of the body is equally distributed on the draw-bars, and means for connecting the cables to the draw-bars.

6. In an equalizer for connecting a body to a plurality of hoisting cables, a first lever having one end pivotally connected to the body, a second lever, means for pivotally connecting one end of the second lever to the free end of the first lever, means for pivotally connecting a portion of the second lever intermediate its ends to the body, means for connecting a cable to a portion of the first lever intermediate its ends, and means for connecting another cable to the free end of the second lever.

HARRY H. VANDERZEE. 30
